UNITED STATES PATENT OFFICE.

WILLIAM MENGE, JR., OF DOLGEVILLE, NEW YORK, ASSIGNOR TO DOLGEVILLE FELT SHOE COMPANY, OF DOLGEVILLE, NEW YORK, A CORPORATION OF NEW YORK.

DESIGN FOR A SHOE.

48,189.

Specification for Design.

Patented Nov. 23, 1915.

Application filed August 17, 1915. Serial No. 46,218. Term of patent 3½ years.

To all whom it may concern:

Be it known that I, WILLIAM MENGE, Jr., a citizen of the United States, residing at Dolgeville, in the county of Herkimer and State of New York, have invented a new, original, and ornamental Design for Shoes, of which the following is a specification, reference being had to the accompanying drawing, forming part thereof.

The figure of the drawing is a plan view of a shoe, made according to the original ornamental design, which I have invented.

The design involves, more particularly, the forming of what is termed the "tongue"

in the upper of a shoe, in the form of a shield, of a material of a different color from that of the vamp, with a scalloped border surrounding it. This, and the ornamental border around the opening of the shoe define very effectively the shield, and produces an attractive effect.

I claim as my invention:

The original ornamental design for a shoe, as shown in the drawing.

WM. MENGE, JR.
